SET-UP CONTAINER

Samuel N. Leopold and Henry K. Powell, Chicago,
Ill., assignors to Morris Paper Mills, Chicago,
Ill., a corporation of Illinois

Application October 2, 1933, Serial No. 691,743

9 Claims. (Cl. 229—5.5)

This invention relates to containers for the packing or packaging of commodities, and pertains particularly to containers of the type which may be manufactured and shipped in knocked-down or substantially flat condition and may be set up at the point of use. While not limited to such, it finds particular utility in the construction of such containers from paper board or the like.

A general object of the invention is the provision of an improved container structure which may be completely fabricated at the factory, packed and shipped in knock-down condition in a space which represents only a small fraction of its volumetric capacity, which may be readily and quickly set up or assembled at the place where it is to be used or filled; which when so set up will constitute a secure, tight and strong container and protection for its contents.

A particular object of the invention is the provision of a container structure possessing the above mentioned characteristics and which may be manufactured at low cost.

Another object is the provision of such a container structure wherein the two end closures are interchangeable.

Other and further objects will be pointed out or indicated hereinafter or will be apparent to one skilled in the art upon an understanding of the invention or its employment in use.

For the purpose of aiding in a disclosure of the invention, we show in the accompanying drawing forming a part of this specification, and herein-after described, certain structural embodiments of it, but it is to be understood that these are presented for purpose of illustration only, as we are aware that the invention may be embodied in other forms. Hence the present description and disclosure of the specific examples are not to be construed in any fashion calculated to limit the appended claims short of the true and most comprehensive scope of the invention in the art.

In the drawing,

Fig. 1 is a perspective view illustrating a cap or end closure for a container, parts being unfolded for the purpose of more clearly showing the construction;

Fig. 2 is a part elevational and part sectional elevational view of an end portion of a container, same serving to illustrate the construction and assembled relationship of a cap or end closure and a tubular body portion; and

Fig. 3 is a perspective view, partly in elevational section, illustrating the construction and assembled relationship of a cap or end closure and a somewhat different tubular body portion.

The nature of the invention will be most quickly ascertained from the illustrative embodiments shown in the drawing, which will now be described. In the form shown, the container comprises a tubular trunk or body portion and two caps or end closures, the latter being identical or interchangeable, although it is to be understood that such interchangeability is not an essential feature of the invention.

The cap or end closure is shown in Fig. 1, in a partly disassembled condition. It is formed of a sheet 10 of paper board or the like, which, for a cylindrical or frusto-conical container, is of approximately circular outline, its outer portion being slotted to form tongues 11, which extend in generally radial directions from its central or body portion. A thin hoop 12, which may be made of paper board, rests upon the end sheet 10 in concentric relationship therewith, and the tongues 11, which are spaced from one another by flaring notches, are bent up against the outer side of the hoop 12, over the rim thereof and downwardly against the inner side of the hoop. The intervening notches are so proportioned that when thus folded about the hoop, the tongues 11 abut one another margin to margin. Preferably the tongues are fixed individually to the outer and inner sides of the hoop by adhesive, although such fastening of the tongues is not essential. The end portions of the tongues, designated 11a, which rest against the inner side of the hoop, form an inwardly projecting ledge or shoulder, as shown in Fig. 2.

The container side or trunk member 14 is a tube or sleeve of flexible material, such as paper board, and preferably is formed with longitudinal creases 14a, as in accordance with the disclosure in our co-pending application Serial No. 644,809, filed November 29, 1932. It is adapted to be collapsed to substantially flat condition, or set up in a substantially cylindrical form.

To provide for the connection of the end closure with it, the trunk member may be provided at its end with a narrow peripheral strip 15, secured by adhesive to its outer side and projecting therefrom as a shoulder or ledge. The width of this strip 15 is slightly less than the space between the margin of the ledge 11a and the end sheet 10 of the end closure. The external diameter across the strip 15 being somewhat greater than the internal diameter across the ledge 11a, and the end of the trunk member being inserted within the cap or end closure, the margins of the strip 15 and ledge 11a will be brought to an overlapping relationship, as illus-

trated in Fig. 2, and an effective connection of the end closure to the trunk member provided. It is to be observed that this method of connection may be employed at either or both the 5 top and bottom ends of the container. It is apparent also that the hoop 12 may be either of cylindrical form, or of frusto-conic form flaring toward the end sheet 10.

In Fig. 3 is illustrated another arrangement 10 for connection of the end closure to the trunk member, which arrangement may be most advantageously employed for the connection of the bottom end closure. It will be seen that the tubular trunk member 14 is provided at its lower 15 end with a plurality of tongues 16 and short longitudinal slots 17. Such construction of the trunk member is described in more detail in the application identified above. An end closure of the above described construction being provided, the 20 trunk member is inserted within the hoop, the tongues 16 being turned radially inward so as to rest upon the inner surface of the end sheet 10. Then a wedging disk 18, of a diameter somewhat greater than the internal diameter of the trunk member, is pressed down into the latter and 25 within the compass of the hoop of the end closure. When it passes the ledge 11^a, the wedging disk 18 will spring the portions of the trunk member wall between the slots 17 outwardly to positions 30 below the ledge, and hold them securely wedged in that location against the inner side of the hoop 12. So assembled, the ledge 11^a, overhanging the outwardly wedged portions of the trunk member wall, will hold the trunk member against 35 withdrawal from the hoop.

It will be appreciated from the foregoing that identical end closures may be used to form a bottom construction such as illustrated in Fig. 3 and either a bottom or top construction as illustrated in Fig. 2.

Depending on the manner in which they are folded and secured, the portions of the tongues at the outer side of the hoop member may either conform to the curvature thereof, or may be 45 straight, or more nearly straight in the circumferential direction. Consequently, the peripheral contour of the end closure may be either approximately circular or polyhedral. The hoop member holds the tongues against separating or flaring, and the tongues, by virtue of their marginal abutment one with another, reinforce the hoop member against collapsing.

The construction provides a secure and strong 55 container which may be manufactured economically, packed for shipment in a space which is quite small as compared to its capacity, and which may be set up very easily at the place where it is to be filled.

What we claim is:

60 1. In a container, an end closure comprising a hoop member and an end sheet covering and

closing one end thereof and having marginal tongues folded across the outer side and margin of the hoop member and with their extremities turned in against the inner side thereof, and a flexible tubular trunk member having its end portion extending within the hoop member and provided with a peripheral shoulder interposed between the end sheet and the in-turned extremities of the tongues. 5

2. An end closure for a container, comprising 10 a hoop member, and an end sheet having a body portion covering and closing one end thereof and having marginal tongues folded across the outer side and margin of the hoop member and with their extremities turned inwardly against the inner side thereof and terminating at a distance from the body portion of the end sheet to afford 15 an intervening channel.

3. An end closure as specified in claim 2 and wherein said tongues are secured individually to 20 the hoop member.

4. An end closure as specified in claim 2 and wherein said tongues are disposed in marginal abutment with one another and are secured to 25 the hoop member.

5. A container comprising the combination with an end closure as specified in claim 2, of a flexible tubular trunk member having an end portion extending within said hoop member, and a wedging disk holding portions of the trunk 30 member wedged outwardly between the body portion of the end sheet and the extremities of the tongues.

6. An end closure as specified in claim 2 and wherein the peripheral contour afforded by the 35 tongues about the hoop member is approximately circular.

7. An end closure as specified in claim 2 and wherein the contour afforded by the tongues about the hoop member is polyhedral. 40

8. In a container, the combination with a tubular trunk member having an outwardly jutting peripheral portion adjacent its end, of an end closure comprising an end sheet having a body portion covering the end of the trunk 45 member and marginal tongues bent angularly from the plane of the body portion and their ends turned reversely so as to extend toward the body portion but terminating at a distance therefrom to afford an intervening channel, and a hoop 50 member enfolded by said tongues and holding them against flexion away from the trunk member, the outwardly jutting portion of the trunk member being disposed in said channel.

9. In a container, a construction as specified 55 in claim 8 and wherein the lateral margins of the juxtaposed tongues are contiguous to one another.
